Inventor

UNITED STATES PATENT OFFICE

DANIEL L. BRAINE, OF BROOKLYN, NEW YORK, ASSIGNOR TO THE RAIL JOINT COMPANY, OF NEW YORK, N. Y., A CORPORATION OF NEW YORK

RAIL-JOINT BAR

Application filed January 7, 1930. Serial No. 419,076.

This invention relates to rail joint bars, and has in view to provide certain improvements designed to increase the utility of such bars from an economic manufacturing and maintenance standpoint, and also to render them considerably more durable and satisfactory in service.

As is well known, rails in service partake of a perceptible wave motion when traffic passes over them, the rails being depressed where they are subjected to load and tending to spring upward to either side of the points of application of the load, especially in advance of such points with reference to the direction of movement of the load along the rails, with the result that all parts of the rails partake of a more or less pronounced vertical movement, which has been the direct cause of early deterioration of the rail ends and of prior rail joint bars.

As heretofore generally constructed and used, rail joint bars have had their respective rail end engaging portions formed of equal weight and strength throughout their lengths, with the result that the end portions of the bars were capable of sustaining the same loads as other portions of the bars. Consequently, with such bars clamped rigidly against the sides of the meeting ends of a pair of rails, the end portions of the bars have constituted in effect fulcrums about which the end portions of the rails have in effect pivoted with the result that the vertical movement of the ends of the rails has been particularly pronounced. This in turn has resulted in pounding with consequent mutilation of the ends of the rails and also in excessive wear on the fishing surfaces of the rails and the joint bars, especially at the center of the latter, due both to pounding of the rail ends and to the resulting sliding contact of the rail ends with the joint bars, causing rapid abrasion of these surfaces. In other words, rail joints as heretofore generally constructed and used have served to in-

terrupt the natural wave motion of the rails where they are joined together and this in turn has resulted in various harmful stresses and strains being set up in the rails and the joints with the consequent development of the foregoing and other unsatisfactory and unsafe track conditions.

Accordingly, one of the important purposes of the present invention is to provide a joint bar involving a novel distribution of metal designed to afford strength where strength is needed to sustain loads imposed on the rails at the ends thereof, and at the same time to enable the wave motion of the rails to be transmitted substantially uninterruptedly through the joint, so that, insofar as concerns this wave motion, a plurality of rails connected together by the present joint bars act substantially as a single continuous rail. Thus, pivoting of the end portions of the rails is substantially eliminated with consequent substantial elimination of pounding of the rail ends and sliding abrasive contact between the rails and the joint bars, thereby assuring safe joints and maximum life both of the rails and of the joint bars.

The metal from which rail joint bars are formed is costly. Therefore any excess metal contained in a bar over and above that essential to the required safety factors may be considered as waste. Accordingly, another important purpose of the present invention is to provide a joint bar having a novel distribution of metal as aforesaid and which is composed of a minimum amount of metal, considerably less metal in fact than has heretofore been considered necessary to be embodied in a bar of corresponding size. Consequently, production costs are reduced and, due to the relatively long life of the present bar, maintenance costs are minimized.

The invention also contemplates, and has for one of its additional important purposes, the provision of a rail joint bar which takes loading engagement with the head fillets of

the rails and which has head clearance from the under faces of the rail heads; and which embodies the desirable features of a so-called toeless bar, these features lending themselves admirably to incorporation in a bar having a novel distribution of the metal thereof in accordance with the present development.

With the foregoing and other purposes in view, the invention consists in the novel construction and in the novel combination and arrangement of features as will be herein-after more fully described, illustrated in the accompanying drawings and defined in the appended claims.

In the drawings, wherein like characters of reference denote corresponding parts in the different views:—

Figure 1 is a perspective view of a rail joint illustrating one practical embodiment of the present joint bar.

Figure 2 is a side elevation of the structure illustrated in Fig. 1; and

Figs. 3, 4, 5, 6 and 7 are cross-sections, respectively, on the correspondingly numbered section lines of Fig. 2.

While the features of the invention are susceptible of structural modification in various respects without departing from the spirit or scope of the invention, and while some or all of them are capable of incorporation in rail joint bars of different types, they are especially desirable and beneficial when embodied in a so-called compromise or step joint bar used, as is well understood, for connecting and holding the meeting ends of rails of dissimilar section with their surface and gage in alinement. Accordingly, for purposes of best illustrating said features, same have been shown in the drawings as incorporated in a joint bar of the compromise type, the bar being designated generally as A and the rails of dissimilar section connected thereby being designated as R, R', respectively.

As usual, the bar A consists of the rail end engaging or fishing sections 1 and 2, respectively, each consisting of a web 3, a head 4 and a foot flange 5, the sections 1 and 2 being vertically and laterally offset with respect to one another in this instance to compensate for the difference in height and section of the rails.

In carrying forward the present developments the bar A preferably is provided at the outer side thereof with a medial enlargement designated at 6 designed to reinforce and strengthen the bar at the junction of the sections 1 and 2 so as to provide a rigid support for the rail ends. Obviously, this enlargement or medial reinforcement may take different shapes, but preferably it is located between the inside pair of bolt holes and does not extend below the base of the high rail. Thus, at the outset, provision is made in the present bar to render the medial portion thereof of ample strength to sustain the

greatest loads to which the extreme end portions of the rails may be subjected.

Further, in carrying forward the invention, each section 1 and 2 of the bar is formed of progressively less thickness and weight from the medial portion of the bar to the end thereof. This reduction in the section and weight of the sections 1 and 2 towards their outer ends likewise may be effected in different ways, but preferably, without altering the height of the sections, the reduction is effected by imparting to the outer face of each section a stepped formation lengthwise thereof. That is to say, each section 1 and 2 is of maximum thickness throughout a portion of its length adjacent to the medial portion of the bar, as indicated at 7, and then towards its outer end is stepped inwardly as indicated at 8, being thinnest and of least weight and strength at its free end. Each section may be provided with any desired number of stepped portions. Three, however, is considered a minimum and practical number, considering the medial enlargement 6 as one of said portions.

It has been found that the ends of a joint bar are required to sustain very little load and that they are subjected to little or no wear. Hence, the ends of the sections 1 and 2 may be formed relatively thin and thus rendered sufficiently yieldable under load to enable the wave motion of the rails to be transmitted from one to the other substantially uninterrupted through the joint. That is to say, due to the decreased weight and strength of the outer end portions of the sections 1 and 2 of the present bar, said portions do not act as fulcrums but to the contrary yield with the rails when load is imposed on the latter above and adjacent to said portions so that pivoting of the end portions of the rails is practically eliminated. Therefore, pounding of the rail ends with consequent sliding abrasive contact between the latter and the joint bars also is practically eliminated. Thus, rails connected by means of the present joint bars act substantially in the nature of a single continuous rail as regards the wave motion of the rails, and longevity of both the joint bars and the rails is assured.

Preferably the successively reduced portions of the present bar are of substantially equal length and the percentage of reduction of cross sectional area of each successive outer section with respect to the thicker section next adjacent thereto is the same, or in other words the percentage of reduction of each successive section is directly proportionate to the section adjacent thereto, thus to render the bar of progressively increasing weight and strength towards its center to compensate for the greater loads imposed on the medial portion of the bar. In this way the bar possesses the necessary weight and strength

throughout its length with a most economical use of metal.

In order to maintain the bolt engaging faces of the bar in a common plane, the outer bolt holes may be surrounded by bosses 9 formed on the outer faces of the thinner portions of the bar, these bosses serving in addition to reinforce the bar in the vicinity of the outer bolt holes.

The present bar preferably is both head-free and toeless. That is to say, the head of the present bar has loading engagement with the head fillets of the rails and clearance from the under faces of the rails, and the foot flange 5 is terminated either flush with or inwardly of the edges of the rail flanges. In a headfree rail joint the resultant of the forces imposed on the joint is directed inwardly in the vicinity of the neutral axis of the bar, while a toeless bar involves a distribution of metal preserving a balance of the bar above and below the neutral axis by in substance crowding into these portions of the bar an amount of metal substantially equal to or less than the amount of metal employed generally to provide a reinforcing toe or girder extending along the bar at the edge of the foot flange. Thus, as is manifest, in a bar of the present type where the sections 1 and 2 are of reduced weight and strength towards their outer ends, it is extremely beneficial to provide for directing inwardly the forces imposed on the bar whereby the relatively weak ends thereof are rendered capable of sustaining such forces, and to embody in the reduced portions of the bar a distribution of metal in accordance with a toeless bar to render the reduced portions of the bar of maximum strength proportionate to the amount of metal embodied therein.

While, as heretofore stated, it is preferred to form the present bar by altering the outer contour and without disturbing the inner contour thereof, obviously the same beneficial results may be obtained by altering only the inner contour of the bar or by altering both the outer and the inner contours thereof.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:—

1. A rail joint bar of progressively decreasing thickness from the medial portion thereof towards its ends, said bar being inclusive of a head and a foot flange, the former being shaped for loading engagement with the head fillets of the rails and for clearance from the under faces of the heads of the

rails, and the latter being formed to terminate inwardly of the edges of the rail flanges.

2. A rail joint bar inclusive of portions of different thickness, said portions having bolt holes therein, respectively, and a boss on the portion of least thickness surrounding the bolt hole therein, the outer face of said boss being flush with the outer face of the other portion having a bolt hole therein.

In testimony whereof I hereunto affix my signature.

DANIEL L. BRAINE.
